LOG LOADING HOOK

Wilbur Stoddard Salisbury, Winchester, Idaho

Application October 31, 1944, Serial No. 561,218

5 Claims. (Cl. 294—82)

This invention relates to improvement in log hooks and has for its object to provide a hook specially adapted for loading heavy timber.

Another object of the invention is to provide a log loading hook, having a cup or bell formed with apertures through its rear wall whereby the cup may be quickly cleaned of packed snow, ice, bark or other debris.

A further object of the invention is to provide a log hook, the body of which is formed of manganese steel and the point of which is formed of tool steel.

A still further object of the invention is to provide a log loading hook having a removable cup and separable point.

Other features and advantages will become more readily apparent from the following description and the accompanying illustrative drawing in which:

Figure 1 is a perspective view of my log loading hook,

Figure 2 is a sectional view on line 2—2 of Figure 1,

Figure 3 is a rear elevation of Figure 2, and

Figure 4 is a front elevation of a cup member.

Like reference characters indicate like parts throughout the following specification and in the several views in the drawing and in which 10, indicates my log loading hook which comprises a body 11, the right angular terminal 12, of which is provided with a tapering slot 13, extending therethrough and on a line parallel with the upper arm 14, of said body. A cup or bell 15, provided with a rearwardly extending tapered shank 16, adapted to seat in said slot 13, is also provided with a central bore 17, which extends centrally through said shank to receive the shank 18, of the point 19. The terminal of the shank 18, is screw-threaded and projects beyond the rear wall 20, of said arm 12, to receive the nut 21, whereby the point and cup are held secure against the enlarged washer 22, on the outer end of said shank 18, whereby the cup and the point are held to the arm 12.

The diameter of the cup 15, is sufficiently greater than the width of said end 12, whereby bores 23 and 24, in the wall 25, of the cup will escape said member 12, on each side thereof to permit punching out of debris of any kind which may fill the cup in using the same. The annular edge 26, of the cup is provided with a series of scallops 27, extending therearound to provide means for more securely biting into the timber being loaded.

It is thought that persons skilled in the art

to which the invention relates will be able to obtain a clear understanding of the invention after considering the description in connection with the drawing. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to protect by Letters Patent is:

1. In a device of the character described a body member having a depending arm with a tapered slot extending through its terminal end, a cup having a shank shaped to fit said slot and means for securing the shank in said slot, said cup having a central bore extending through its wall and said shank, and a point having a shank extending through said bore, said cup being of greater diameter than the width of said terminal and bores through said cup wall on each side of said terminal, and said cup having a scalloped edge.

2. In a device of the character described a body member having a depending arm with a tapered slot extending through its terminal end, a cup having a shank shaped to fit said slot and means for securing the shank in said slot, said cup having a central bore extending through its wall and said shank, and a point having a shank extending through said bore, and said cup being of greater diameter than the width of said terminal and bores through said cup wall on each side of said terminal.

3. In a log hook, a body having a depending member with a tapering slot in its end, a cup having a shank shaped to fit said slot, said cup being of greater diameter than the width of said end and provided with a series of bores extending through the cup and beyond said end.

4. In a device as described a body having an arm with a slot and a cup having a shank shaped to fit the slot, said cup being of greater diameter than the width of said arm and having bores therethrough on each side of the arm whereby debris in the cup may be quickly dislodged.

5. In a device as described, a logging hook cup comprising a cup, a shank having a right-angular portion and a terminal of less width than the diameter of the cup, said cup including a bottom wall provided with evenly spaced bores, means for securing the cup to said terminal, and said bores being so spaced as to avoid said terminal.

WILBUR STODDARD SALISBURY.
